UNITED STATES PATENT OFFICE.

MAHLON E. LAYNE, OF HOUSTON, TEXAS.

WELL-SCREEN.

1,088,078.

Specification of Letters Patent. Patented Feb. 24, 1914.

Application filed April 1, 1913. Serial No. 758,142.

To all whom it may concern:

Be it known that I, MAHLON E. LAYNE, a citizen of the United States, residing at Houston, in the county of Harris and State 5 of Texas, have invented certain new and useful Improvements in Well-Screens, of which the following is a specification.

The invention relates to well screens, the apparatus embodying the present invention constituting a modification of the apparatus disclosed in my Patent No. 1,062,717, issued May 27, 1913. The invention has for its objects, the provision of an improved type of screen which can be more 10 easily sunk, and one in which the tendency of the front end of the screen to deflect laterally in the driving operation is substantially eliminated. Certain embodiments 15 of the invention are illustrated in the accompanying drawing wherein—

Figure 1 is a vertical section through the ground, showing the metal screen in side elevation with a portion thereof broken away; Fig. 2 is a side elevation of a modification; and Fig. 3 is a side elevation of the lower end of still another modification.

The screen is of metal, and may be perforated in order to provide for the inflow of water or other liquid in any manner 20 known in the art. The screen may be made of ordinary tubing, but is preferably made of sheet metal bent into cylindrical form, the sections thus formed being secured together to provide a screen of any desired 25 length.

In the form of screen illustrated the perforations are of the type illustrated in my Patent #1,001,655, issued August 29, 1911, such perforations being in the form of circumferential slits. These slits are formed by 30 means of opposing serrated dies, one inside the tube and the other outside the tube, which dies are brought toward each other and shear out the slits and bend the strips 35 of metal between the slits into the angular positions indicated in the drawings. This form of perforation has special advantages, as pointed out in the said Patent No. 1,001,655, but such feature constitutes no 40 part of my present invention.

The screen as illustrated in Fig. 1 comprises three portions, A, B, and C, the extreme lower portion A being cylindrical, the portion B thereabove being tapering, 45 and the portion C above the tapering portion being cylindrical. The perforations 1

as above described are placed on those portions of the screen exposed to the water-bearing strata, the upper portion of the screen not exposed to water-bearing strata 50 and the portion A being left unperforated as indicated in Fig. 1. The lower edge of the section A is provided with a cutting shoe 2 which may be of any approved form, and serves to facilitate the sinking of the tube 55 into the ground.

Surrounding the screen above the tapering portion B and supported thereby, is the tubular envelop of finely divided screening material 3 preferably of gravel, such tubular envelop bearing at its inner surface upon the screen, and at its outer surface upon the clay or other material through which the tube is sunk.

In positioning the screen the gravel 3 is 75 inserted as the tube moves down and as the dirt is removed from the interior of the tube. The weight of the gravel thus inserted assists in the downward movement of the tube, and serves to prevent the soil 80 around the tube from caving, the advantages of this general type of construction being pointed out in my Patent No. 1,062,717 referred to.

The use of the straight cylindrical portion 85 A below the tapering portion B has been found to be of advantage, inasmuch as such construction tends to prevent the tube from working laterally during its descent, as is the case where the flared or tapering portion is at the extreme lower end of the tubing. The lower cylindrical portion A therefore serves as a guide, and causes the tube to descend in a true vertical path. The construction is of particular 90 advantage where the soil formation is uneven and one portion of the end of the tube engages a formation harder or more resistant than another portion of the tube, as in such formations the tendency of the end of 100 the tube to be deflected laterally is greatly increased. The length of the portions A and B and the inclination of the portion B may be varied to suit conditions, and any type of perforation may be employed. 105

Fig. 2 illustrates a modified type of construction wherein the tapering portion D of the tube is at its extreme lower end, the cylindrical guiding portion A of Fig. 1 being omitted. The portion E above the tapering portion D is cylindrical and corresponds to the portion C of Fig. 1. The per-

forations 1' are formed in the same manner as the perforations 1 in the structure of Fig. 1, and the screening envelop is applied and performs the same function as in the structure of Fig. 1. A cutting shoe 2' is applied to the lower end of the section D. The construction has the advantage over that of my said Patent No. 1,062,717 in that it is easier to construct a screen having the lower section only tapered than it is to construct one which tapers all the way from its lower to its upper end. The construction also has the further advantage that the gravel envelop surrounding the metal screen has a maximum uniform thickness clear from the upper end of the section D to the top of the screen, instead of an envelop which decreases in thickness from the top of the well to the lower end thereof. The body of gravel and the screening capacity is therefore correspondingly increased with this type of apparatus, although the guiding feature incident to the use of the cylindrical section A of Fig. 1 is not present, the construction of Fig. 1 having a marked superiority in this respect. The general features of advantage incident to this type of construction employing the gravel envelop are fully set forth in my said Patent No. 1,062,717, which is the generic case in so far as the fundamental feature involved is concerned.

Fig. 3 illustrates a modification of the structure of Fig. 1, the distinction being that the lower cylindrical portion A² is provided with slots 1² instead of being left unperforated, the construction being desirable in cases where the lower portion A² is embedded in a water bearing stratum instead of in clay or other non-water bearing material. The screen is in other respects the same as in the construction of Fig. 1.

What I claim is:

1. A well screen comprising a perforated metal tube having its upper portion cylindrical and a portion adjacent the lower end

tapering outwardly from the cylindrical portion, and a tubular envelop of loose screening material extending upward from the tapering portion of the tube and supported thereon and bearing at its inner surface against the tube and at its outer surface against the material in which the screen is located, the thickness of the walls of the tubular screening envelop being such that it may be inserted as the tube moves down. 55

2. A well screen comprising a perforated metal tube having its extreme lower end cylindrical, a portion above such cylindrical portion tapering inward and a cylindrical portion above such tapering portion, and a tubular envelop of loose screening material extending upward from the tapering portion of the tube and supported thereon and bearing at its inner surface against the tube and at its outer surface against the material in which the screen is located, the thickness of the walls of the tubular screening envelop being such that it may be inserted as the tube moves down. 60 65

3. A well screen of perforated metal tubing comprising a straight cylindrical portion at the lower end, a tapering portion thereabove, and another straight cylindrical portion above the tapering portion. 70

4. A well screen of perforated metal tubing comprising a tapering portion largest at its lower portion adjacent the lower end of the tube, guide means projecting downwardly from the lower edge of the tapering portion and provided with cutting means, 80 and a straight cylindrical portion above the tapering portion. 75

In testimony whereof I have hereunto signed my name in the presence of the two subscribed witnesses.

MAHLON E. LAYNE.
